UNITED STATES PATENT OFFICE.

WILLIAM U. GRIFFITHS, OF PHILADELPHIA, PENNSYLVANIA.

DESIGN FOR A SUSPENSION PIPE-SECTION.

SPECIFICATION forming part of Design No. 34,101, dated February 19, 1901.

Application filed December 17, 1900. Serial No. 40,216. Term of patent 7 years.

To all whom it may concern:

Be it known that I, WILLIAM U. GRIFFITHS, a citizen of the United States, residing in the city of Philadelphia, in the county of Philadelphia and State of Pennsylvania, have invented and produced a new and useful Design for Suspension Pipe-Sections, of which the following is a specification, reference being had to the accompanying drawing thereof.

10 In the drawing, the accompanying figure is a view in perspective of a suspension pipe section showing my new design.

As shown in the drawing, the leading or material feature of my design consists of a 15 pipe *a*, having the circumferential bead *b* at its lower end, and the flange *c* at its upper end, said flange extending outward from the

body of the pipe *a*, in a plane at right angles to the axis of said pipe, and having a number of curved slots *d* concentric with respect to 20 the axis of the pipe.

Having thus described my invention, what I claim as new and desire to secure by Letters Patent is:

The design for a suspension pipe section, as 25 herein shown and described.

In testimony that I claim the foregoing as my invention, I have hereunto signed my name this fourteenth day of September, A. D. 1900.

WM. U. GRIFFITHS.

In presence of—

S. SALOME BROOKE,
THOS. K. LANCASTER.
